UNITED STATES PATENT OFFICE.

JAMES E. RATCLIFF, OF DAWSON, ILLINOIS.

IRONING-TABLE.

No. 850,966.

Specification of Letters Patent.

Patented April 23, 1907.

Application filed April 2, 1906. Serial No. 309,357.

To all whom it may concern:

Be it known that I, JAMES E. RATCLIFF a citizen of the United States, residing at Dawson, in the county of Sangamon and State of Illinois, have invented a certain new and useful Ironing-Table, of which the following is such a full, clear, and exact description as will enable others skilled in the art to make and use my said invention.

10 This invention relates to folding ironing-tables provided with hinged ironing-boards and detachable sleeve-boards.

15 The purposes of this invention are to provide an ironing-table having a hinged ironing-board and a detachable sleeve-board and combining lightness, strength, and rigidity, and so constructed and arranged that when extended both the ironing-board and the sleeve-table will be in convenient position for use, and when folded the several parts of the ironing-table will be compactly disposed relative to each other, so that the ironing-board may be conveniently carried, and when stowed away will occupy little 25 space.

With these ends in view my invention consists in the novel features of construction and combinations of parts shown in the annexed drawings, to which reference is hereby 30 made, and hereinafter fully described and finally recited in the claims.

Referring to the drawings, in which similar reference-numerals designate like parts in the several views, Figure 1 is a perspective view of the ironing-table extended. Fig. 2 is a central vertical longitudinal section through the extended ironing-table, and Fig. 3 is a similar section through the folded ironing-table.

40 The entire ironing-table frame is of wood, of suitable dimensions for the purpose.

Side pieces 1 are connected by cross-pieces 2, a top plate 2^a, and a bar 3. The contiguous intermediate cross-pieces 2 are parallel 45 and are such a distance apart that when the table is folded the leg 9^a of the sleeve-board will fit between the cross-pieces and will support the sleeve-board between the ironing-board and the main frame, as shown in Fig. 3. The side pieces 1 have notches 1^a. The

cross-piece 3 has a mortise 3^a. Legs 4 are connected by cross-pieces 5, and the upper cross-piece 5 is secured on the legs 4 by metal straps 6, preferably of galvanized iron.

The board 7 is shaped substantially as shown, and near the inner end thereof parts of the board are cut away to fit that part of the board between the side pieces 1 and form shoulders 7^a, which when the table is extended rest on the upper edges of the side pieces 1. The board 7 is provided with fixed blocks 7^b. A cross-piece 8 is secured on the under side of the board 7 and is also secured to the blocks 7^b. Bolts 10 connect the blocks 7^b with the side pieces 1, so that the reduced part of the board may turn between the side pieces 1. The sleeve-board 9 has a fixed leg 9^a and a tenon 9^b, which fits in the mortise 3^a in the bar 3. Braces 12 are pivotally connected with the side pieces 1 and the legs 4 by bolts 13.

When the ironing-board is extended, as shown in Figs. 1 and 2, the reduced part of the board 7 lies under the cross-piece 5, and the cross-piece prevents downward turning 75 of the outer end of the board. The tenon 9^b of the sleeve-board lies in the mortise 3^a, and the leg 9^a supports the sleeve-board in a horizontal position above the board 7. If it is not desired to use the sleeve-board, it may be 80 easily detached without disturbing the board 7. When the ironing-table is folded, as shown in Fig. 3, the leg 9^a of the board 9 fits between the contiguous and parallel intermediate cross-pieces 2 and supports the 85 sleeve-board on the cross-pieces. When the ironing-table is extended, the cross-piece 5 lies in the notches 1^a and supports the upper part of the frame and the braces 12 prevent accidental turning of the legs. 90

Having fully described my invention, what I claim as new, and desire to secure by Letters Patent, is—

In an ironing-table the combination of a main frame having side pieces and contiguous parallel intermediate cross-pieces, an ironing-board pivotally connected with and adapted to lie upon the side pieces of the main frame and a sleeve-board connectible to the main frame and having a leg adapted 95 100

to support the sleeve-board horizontally upon the ironing-board when the ironing-table is extended; also adapted to fit between the intermediate cross-pieces of the main frame and support the sleeve-board between the ironing-board and the main frame when the ironing-table is folded.

In witness whereof I have hereunto subscribed my name, at Springfield, Illinois, this 16th day of March, 1906.

JAMES E. RATCLIFF.
